PIPE LINE TREATING SYSTEM

William Woelflin, Long Beach, Calif., assignor to
 Petroleum Rectifying Company of California,
 Los Angeles, Calif., a corporation of California

Application August 8, 1932, Serial No. 627,910

23 Claims. (Cl. 204—24)

My invention relates to the electric dehydratation of petroleum emulsions, and more particularly to a novel treater which finds particular utility in this art, though certain of the features 5 of this treater are not limited thereto.

It is often necessary to transport petroleum through pipe lines for considerable distances by pumping from one temporary storage to another storage, and it is an important object of the 10 present invention to provide a pipe-line treater which is connected in such a pipe line so that the emulsion flowing through the pipe line is electrically treated before being discharged into a more remote section of the pipe line or into a 15 storage or settling means. Such a treater can be of relatively small dimensions and need not necessarily include a separating means adjacent thereto.

It is a further object of the invention to utilize 20 a plurality of such pipe-line treaters spaced along a pipe line carrying petroleum which may be in the form of an emulsion. If no separating means is provided at each treater, each treater will merely agglomerate the water particles of such 25 an emulsion into somewhat larger masses. Several advantages thus accrue. Not only is the treatment effected in steps, but with certain gas-blown emulsions the particle-size can be progressively increased by successive treatments, and 30 there will be less tendency for an extremely tight emulsion to be formed due to the agitation caused by turbulent flow in the pipe. Such treaters spaced along a pipe line will insure that the water particles will be of larger size than would 35 otherwise be the case. This structure is also advantageous in that it delivers to the treater adjacent the settling means an emulsion composed of larger water particles suspended in a continuous phase of oil, this emulsion being relatively easy to treat to effect the final agglomeration 40 preparatory to separation. Such a system also permits higher velocities through a pipe line inasmuch as it controls the re-emulsifying tendency caused by agitation in the pipe and decreases the viscosity of the fluid.

It is a further object of the invention to position such a pipe-line treater in the pipe line and preferably below the surface of the ground, thus 50 eliminating piping and being especially valuable in colder climates where operating difficulty is experienced at extremely low temperatures.

Further objects of the invention lie in the construction of the treater, and especially in utilizing 55 a pipe or a section of the pipe line itself as an

electrode, and providing a central electrode extending therein from an adjacent chamber.

The simplified construction is another feature of the invention, the preferred embodiment being formed entirely of conventional pipe fittings. 5

A further object of the invention lies in the provision of a discharge chamber into which the treated emulsion passes, and an insulator chamber opening thereon and in which the insulator 10 is positioned.

It is a further object of the invention to remove the back pressure on such a treater to such an extent that gas is liberated from the emulsion undergoing treatment and enters the 15 space around the insulator.

A further object of the invention is to direct the incoming emulsion centrally into the length of pipe forming the outer electrode and toward the inner electrode, and, in some instances, to 20 supply a dielectric oil to the space around the nozzle and inside the outer electrode.

Another and very important object of the invention is to provide a method and apparatus for protecting an insulator by flowing a stream 25 of dielectric material along the surface thereof to prevent accumulation of conducting material on this surface.

Further objects and advantages of the invention will be made evident hereinafter. 30

Referring to the drawings—

Fig. 1 is a view partially in section illustrating two pipe-line treaters installed in position along a pipe line.

Fig. 2 is a vertical sectional view of the preferred embodiment of the treater.

Fig. 3 is a sectional view taken on the line 3—3 of Fig. 2 and illustrates the insulator protecting system.

Fig. 4 is an elevational view illustrating an alternative form of the invention.

Referring first to the details of the preferred embodiment of the invention best shown in Fig. 2, this treater includes a container or an enclosing structure 10 which may conveniently, though not necessarily, include an intake 11, a length 45 of pipe 12, a discharge 13, a reduction nipple 14, and a connecting nipple 15.

The incoming emulsion flows through an intake section of pipe 18 which forms a part of a pipe line 19, this intake section of pipe extending through a head 20 closing one end of the intake 50 55 T 11. A nozzle 21 is secured or formed on the inner end of the intake pipe 18 and cooperates

therewith in defining a nozzle structure 22. This nozzle structure extends substantially through the intake T 11 and past an opening formed in a leg 24 of this T. The incoming emulsion is thus directed centrally into the length of pipe 12 due to the action of the nozzle structure 22. The discharge end of this length of pipe 12 provides a flange 26 which is secured to the discharge T 13 as shown. A discharge chamber 27 is formed inside the main body of the discharge T 13, this T also providing a leg 28 which preferably extends upward from the discharge chamber 27 and provides an insulator chamber 29 therein, the discharge chamber and the insulator chamber cooperating in defining an enlarged chamber communicating with the interior of the length of pipe 12. If desired a nipple 30 can be secured to the upper end of the leg 28 so as to enlarge the insulator chamber 29 to correspond to the particular insulator utilized.

In Fig. 2 I have shown an insulator 32 mounted in a plate 33 closing the upper end of the insulator chamber 29, the insulator extending downward in this chamber but terminating near the boundary of the discharge chamber 27. The insulator chamber may contain a liquid carrying conducting particles (e. g. such as the emulsion constituents), this liquid contacting the surface of the insulator 32, or this insulator chamber 30 may contain a gas as will be hereinafter set forth. While it is possible for the inner portion of this insulator to extend downward into the discharge chamber 27, it is desirable that the inner end thereof terminate short of the central portion of the discharge chamber so that this inner end of the insulator will not seriously interfere with the flow taking place through this discharge chamber.

Extending completely through the insulator 32 is a conductor means in the form of a rod 35 which carries a pair of supporting arms 36 at the lower end thereof, these supporting arms being bent downward to extend into the discharge chamber as shown. Suitably secured to the lowermost ends of these arms is a rod electrode 38 which extends from the discharge chamber 27 into the length of pipe 12 which forms the outer electrode and terminates in a relatively sharp point 39 which is in axial alignment with and which terminates short of the nozzle 21 so as to pierce the stream of emulsion delivered from the nozzle 21. The annular space between the rod electrode 38 and the outer electrode formed by the length 55 of pipe 12 thus comprises a treating space 40 in which an electric field may be set up from a source such as a transformer 41 providing a secondary winding 42 connected between the conductor 35 and the length of pipe 12.

In the preferred embodiment I prefer to utilize a dry oil pipe 48 communicating through a valve 49 with the interior of the leg 24 of the intake T 11. A dielectric liquid is delivered to this pipe from any suitable source and thus enters the annular space between the body of the T 11 and the nozzle structure 22, this space being indicated by the numeral 50. A stream of dielectric is thus introduced into the outer portion of the length 70 of pipe 12 and may flow through the treating space as an outer envelope around the central stream of emulsion. With other designs of the nozzle 21, it is possible to secure at least some intermixture between the incoming emulsion and 75 the dry oil prior to the time these liquids move

into the annular treating space 40, or as the constituents are moving therethrough.

Difficulty is sometimes experienced with insulators of this type when such insulators have access to a conducting material. The water in the emulsion forms such a conducting material, and a coating or deposit of this material often accumulates on the surface of the inner portion of the insulator through condensation of vapors, or by a mixture of the oil and water being sprayed on the insulator, or by positioning the insulator surface in a liquid carrying conducting particles. Such a coating of conducting material tends to form a conducting path along the surface of the insulator and to cause an arc-over which develops sufficient heat to break the insulator. In the present invention I have developed a system and method for successively preventing such insulator break-downs. In the preferred embodiment a pipe 55 extends from the dry oil pipe 48 and into the insulator chamber 29, the flow of dry oil being controlled by a valve 56. Any suitable distributing or spray means may be utilized for directing the dry oil along the surface of the insulator in such a manner as to cover this surface with a flowing stream of the dielectric oil which tends to wash the surface of the insulator and remove conducting particles. In the preferred embodiment I utilize an annular spray ring 58 provided with a number of downward directed openings or small jets 59 disposed adjacent the surface of the insulator and directing streams of the dry oil into contact therewith, these streams cooperating in forming an envelope which surrounds the insulator and flows downward therealong. These openings comprise an orifice means, though it should be understood that other types of orifice means can be utilized, such as arcuate slots, separate nozzle means, etc., all of such means being included in the term orifice means. In some instances, however, it is not necessary to use this insulator-protecting device, in which case the valve 56 can be closed. In other instances periodic use of this flow of oil along the surface of the insulator is sufficient to prevent break-down thereof.

It is also possible to so operate the treater that the upper end of the discharge chamber 27 and the insulator chamber 29 are substantially filled with a gas, this gas having sufficient dielectric properties to protect the insulator. In the preferred embodiment this can be accomplished by reducing the back pressure on the treater to such an extent that gas is liberated from the emulsion and moves upward to fill the insulator chamber 29 and the upper portion of the discharge chamber 27. When thus operated, the surface of the treated emulsion lies approximately as indicated by the dotted lines 61 of Fig. 2.

This condition may be easily attained by utilizing some means of reducing the pressure in the discharge chamber 27 to such a value that the gas will be liberated. In Fig. 1 I have illustrated two methods of accomplishing this end, namely, by the utilization of either a pump or a column of liquid flowing from the discharge chamber which lowers the pressure therein. The combination including a pump is shown in the left half of Fig. 1, the pump being indicated by the numeral 70 and intaking from a pipe 71 communicating with the connection nipple 15 and discharging into a section of pipe 72 which may either extend directly to a settling tank to effect a separation of the constituents or may form a part of the pipe line 19.

The treater shown in this portion of Fig. 1 is substantially the same as that shown in Fig. 2, corresponding numbers indicating corresponding parts. The unit is preferably mounted in alignment with the pipe line 19 and is preferably positioned in a pit 73 formed below the surface of the ground and lined with concrete. A cover 74 preferably extends over the top and carries an insulator 75 through which the supply leads for the transformer 41 extend. These supply leads are also electrically connected, as by conductors 76, to a motor 77 which drives the pump 78. If a circulation of dry oil is utilized this may be derived from any suitable source not shown, flowing through the pipe 48 previously described, this pipe extending through the cover 74. This positioning of the treater is especially advantageous in cold climates, and, if desired, the interior of the pit may be heated or heat-insulating means may be utilized on the cover 74. As many of these treating units as desired may be installed along the pipe line, as previously described, each unit not only compensating for the emulsification which takes place in the pipe line due to pipe friction, but also agglomerating the water particles into progressively larger droplets so that when the emulsion is moved into the last treater preparatory to separation a quick treatment and subsequent separation will be effected.

Another way in which the treater can be very advantageously utilized is shown in the right half of Fig. 1 wherein the treater is mounted above the uppermost portion of a separating tank 82 including a water outlet 83 and a dry oil outlet 84. Brackets 85 may be utilized for mounting the treating unit above the uppermost portion of the tank, and a discharge pipe 86 may communicate with the discharge chamber 27. This pipe 86 extends downward and communicates with a spray pipe 87 positioned inside the tank, or with other means for introducing the treated emulsion into the interior of the tank 82 for separation. In view of the fact that the treater is mounted above the uppermost level of the tank, a column of treated emulsion will be present in the downward extending portion of the pipe 86 which will reduce the pressure in the discharge chamber 27 so as to allow the liberation of the gas as previously set forth, this column of treated emulsion taking the place of the pump 78.

In this connection a portion of the dry oil flowing through the pipe 84 is conducted to storage or to an additional pipe line through a pipe 89. A small portion of the dry oil is withdrawn through a pipe 90 by a pump 91 driven by a motor 92. This pump circulates the dry oil through a pipe 93 corresponding to the pipe 48 previously described, a portion of this oil flowing into the treating space along with the incoming emulsion, and another portion, if desired, flowing around the insulator through the pipe 55.

It will be understood that it is not in all events necessary to utilize dry oil either for the purpose of protecting the insulator or for moving through the electric field along with the emulsion. Many emulsions can be very successfully treated without the use of such a liquid dielectric. Usually with emulsions having more than approximately 12% water it is desirable to circulate the dry oil. This value is not, however, invariable and depends both upon the size of the treater and other factors of operation.

As a practical example of the operation of such a treater, the length of pipe 12 comprising an

outer electrode may be formed of a piece of 3" pipe and the rod electrode 28 may be from $\frac{1}{8}$ " to 1" in diameter. A nozzle having an orifice of approximately $\frac{3}{8}$ " in diameter gives very satisfactory treatment, and with such a treater an average potential gradient of 13,000 volts per inch across the gap will be very satisfactory, the cuts ranging in the neighborhood of 1.6% or less. Usually more satisfactory treatment will be obtained by the use of small rod electrodes. The pressure on the incoming emulsion is not critical, pressures from 35 lbs. per sq. in. to 200 lbs. per sq. in. giving very satisfactory treatment. It should be understood, however, that these values are only illustrative and that I am not in any way limited thereto.

It is sometimes desirable to preliminarily mix the dry oil and the emulsion before entry into the pipe 12. This may conveniently be done in the form of the invention shown in Fig. 4 in which a T 95 is connected both to the pipe line 19 and to the dry oil pipe 48, the relative amounts of dry and wet oil being proportioned by the setting of a valve 96 utilized in the pipe 48. A mixer 97 may be utilized, if desired, for more intimately mixing the dry oil and the emulsion. Such a mixer may be of the mechanical agitation type or may comprise a conventional mixing valve or other well-known type of mixing apparatus. The mixture then moves through the inlet pipe 18 and the nozzle 21 as previously set forth.

While I have not shown a heating means for heating the incoming emulsion, it will be clear that such heating means may be used as in conventional practice.

One of the features of the present invention lies in the use of a small rod electrode which extends into a pipe forming a central section of a pipe line so that the pipe itself is used as an electrode. This results in a simplified structure and one which is found to be very effective in the treatment of petroleum emulsions especially when utilized in conjunction with a pipe-line treater. Another feature of the invention is the mounting of such a small rod electrode in a chamber adjacent one end of the pipe which forms the outer electrode. This permits the mounting of the rod electrode to be spaced from the main treating space so that no supporting means restricts the flow through the space between the electrodes.

The particular mode of forming the concentric streams of oil and emulsion is also a feature of the present invention, as well as the mode of operation wherein the insulator is surrounded by the gas liberated from the emulsion. The insulator protecting system including the utilization of a flow of dry oil along the surface of the insulator is also a very important feature, as is also the positioning of the insulator in a chamber to one side of the main discharge chamber so that it does not interfere with the main flow of emulsion.

I claim as my invention:

1. In a pipe-line treater, the combination of: a horizontally disposed pipe comprising an outer electrode connected to the pipe line; walls connected to one end of said pipe and forming an enlarged chamber into which said pipe discharges; a horizontal rod electrode extending from said enlarged chamber into said pipe and cooperating with said pipe in defining an annular treating space; insulator means extending sideways in said enlarged chamber toward said rod electrode for mounting said rod electrode to ex-

tend centrally into said pipe; nozzle means extending into the opposite end of said pipe from said walls forming said enlarged chamber and directed toward but spaced from the inner end 5 of said rod electrode; means for supplying the emulsion to be treated to said nozzle means, said emulsion being thus discharged from said nozzle and moving through said pipe and thence into and through said treating space and being there- 10 after discharged into said enlarged chamber, the inner end of said insulator means terminating short of the main stream of emulsion discharged from said nozzle; and means for impressing a potential difference between said rod and said 15 outer electrode.

2. In a pipe-line treater, the combination of: a length of pipe connected to a pipe line and comprising an outer electrode; a nozzle connected to said pipe line and of smaller diameter 20 than said length of pipe and extending into one end thereof to define an annular space therebetween; a rod electrode extending into the other end of said length of pipe and toward said nozzle but terminating a distance therefrom, said rod 25 electrode cooperating with said length of pipe in defining an annular treating space; insulator means supporting said rod electrode in said length of pipe and spaced from the liquid stream discharged from said nozzle; means for establishing 30 a potential difference between said rod electrode and said length of pipe; means for supplying the emulsion to be treated to said nozzle; and pipe means communicating with said annular space between said nozzle and said length 35 of pipe for supplying a liquid thereto dissimilar to said emulsion said liquid flowing from said annular space around the stream of said emulsion discharged from said nozzle whereby said liquid and said emulsion move through said treating 40 space and are discharged from said length of pipe.

3. In an electric treater, the combination of: an outer electrode; walls attached to one end of 45 said outer electrode and forming a discharge chamber into which moves the liquid flowing from said outer electrode; walls forming an insulator chamber at one side of said discharge chamber; an insulator in said insulator chamber and extending toward but terminating short of the 50 central portion of said discharge chamber to be substantially removed from the main body of liquid flowing through said discharge chamber; a rod electrode retained by said insulator and extending into said outer electrode; and means for 55 impressing a potential difference between said rod electrode and said outer electrode.

4. In a pipe-line treater, the combination of: a length of pipe; a pipe T secured to the discharge end of said length of pipe and providing 60 a discharge chamber and an insulator chamber; an insulator mounted to extend into said insulator chamber; a rod electrode retained by said insulator and extending into said length of pipe; means for establishing an electric field 65 between said rod electrode and said length of pipe; and means for supplying the emulsion to be treated to said length of pipe, the treated emulsion moving through said T.

5. In a pipe-line treater, the combustion of: 70 a length of pipe; a pipe T secured to one end of said length of pipe and providing a discharge chamber and an insulator chamber; an insulator mounted to extend into said insulator chamber; a rod electrode retained by said insulator and extending into said length of pipe; means for estab-

lishing an electric field between said rod electrode and said length of pipe; an intake T secured to the other end of said length of pipe and providing a leg; a nozzle extending into said intake T to define an annular space communicating with said leg; means for supplying a dielectric oil to said leg and hence into said annular space; and means for supplying the emulsion to be treated to said nozzle.

6. A combination as defined in claim 5 in which 10 said nozzle extends to a position beyond said leg to direct a central stream of emulsion into said length of pipe.

7. A method of protecting an insulator of an 15 electric dehydrator which extends into a gas-filled space communicating with a conducting medium, which method is characterized by the step of washing the surface of said insulator in 20 said gas-filled space by flowing a dielectric liquid along said surface.

8. A method of protecting an insulator extending 25 into a liquid in a dehydrator which liquid carries conducting particles, which method includes the step of continuously introducing into 30 said liquid and at a section adjacent the surface of said insulator an annular stream of dielectric liquid flowing longitudinally along and in contact with the surface of said insulator.

9. In a pipe-line treater, the combination of: 35 a pair of electrodes defining a treating space; walls forming a discharge space into which flows the treated liquid discharged from one end of said treating space; walls defining an insulator chamber communicating with said discharge space and positioned thereabove; an insulator 40 extending downward in said insulator chamber and mounting one of said electrodes; means for delivering the emulsion to be treated to said treating space, said emulsion being treated therein and flowing into said discharge chamber and 45 said emulsion including a conducting medium tending to accumulate on the surface of said insulator; means for flowing a stream of dielectric oil along the surface of said insulator to protect 50 said surface from contact with said conducting material; and means withdrawing the treated emulsion from said discharge chamber at such rate that gas is liberated from said emulsion due to the absence of excessive back pressure, said gas substantially filling said insulator chamber 55 around said insulator.

10. A method of treating an emulsion flowing 60 along a pipe line, which method includes the steps of: establishing a plurality of electric fields positioned at spaced sections along said pipe line; passing all of the emulsion constituents successively through said fields, each of said fields being of sufficient intensity to coalesce the dispersed droplets of the dispersed phase of said 65 emulsion, this dispersed phase remaining associated with the continuous phase of said emulsion during successive subjection of said emulsion to said fields, at least partial re-emulsification of said emulsion constituents taking place during their flow between said spaced sections to form a modified emulsion of different character from that discharged from the next preceding electric field but not re-emulsified to the degree of the emulsion entering the preceding field whereby 70 said emulsion is successively treated.

11. A method of treating an emulsion flowing 75 along a pipe line, which method includes the steps of: establishing a plurality of electric fields positioned at spaced sections along said pipe line and through which the emulsion constituents 80

successively pass, each of said fields being of sufficient intensity to coalesce the dispersed droplets into larger masses, at least partial re-emulsification of said emulsion constituents taking place during their flow between said spaced sections to form a modified emulsion of different character from that discharged from the next preceding electric field but not re-emulsified to the degree of the emulsion entering the preceding field whereby said emulsion is successively treated until the size of said dispersed droplets become great enough that these droplets will separate when the emulsion constituents are allowed to settle; introducing the emulsion constituents discharged from the last electric field into a settling space; and separately removing the separated constituents from said settling space.

12. A method of treating an emulsion flowing along a pipe line, which method includes the steps of: establishing a plurality of electric fields positioned at spaced sections along said pipe line and through which the emulsion constituents successively pass, each of said fields being of sufficient intensity to coalesce the dispersed droplets into larger masses; adding to the emulsion constituents at sections spaced along said pipe line a dielectric liquid whereby a succeeding field treats the emulsion constituents treated by the preceding fields together with the added dielectric liquid; and separating said emulsion constituents after subjection to the last electric field.

13. A method of dehydrating an emulsion by the use of an electric treater having an insulator chamber in the upper end thereof, which method includes the steps of: moving a stream of the emulsion into said treater; establishing an electric field in said treater of sufficient intensity to coalesce the dispersed droplets of said emulsion into larger masses; and forcibly withdrawing the emulsion constituents from said treater before substantial separation thereof has taken place and at such rate that the pressure in said treater is maintained sufficiently low to liberate gas from said emulsion in said treater, said gas rising to said insulator chamber.

14. A method of dehydrating an emulsion by the use of an electric treater having an insulator chamber in the upper end thereof, which method includes the steps of: moving a stream of the emulsion into said treater; establishing an electric field in said treater of sufficient intensity to coalesce the dispersed droplets of said emulsion into larger masses; forcibly withdrawing the emulsion constituents from said treater before substantial separation thereof has taken place and at such rate that gas is liberated from said emulsion in said treater and rises to said insulator chamber; and withdrawing with said emulsion constituents any excess gas liberated in said treater over and above the quantity of gas necessary to fill said insulator chamber.

15. In combination in an emulsion-treating system: an intake section of pipe through which flows the emulsion to be treated; a length of pipe communicating with said intake section of pipe to receive the emulsion flowing therethrough; electrode means centrally disposed in said length of pipe and extending axially therein; means for insulating said electrode means from said length of pipe; means associated with said electrode means for establishing an electric field in said pipe of sufficient intensity to exert a coalescing action on the dispersed particles of said emulsion; a second section of pipe receiving the electrically

treated emulsion discharged from said length of pipe before substantial separation has been effected whereby said second section of pipe receives the same emulsion constituents as passed through said intake section of pipe and tends to re-emulsify the treated emulsion constituents; an electric treater communicating with said second section of pipe and receiving the emulsion constituents flowing through said second section of pipe in a condition wherein these emulsion constituents are at least partially re-emulsified due to the friction in said second section of pipe, said electric treater including means for establishing an electric field to which said emulsion constituents are subjected said field coalescing the dispersed particles thereof; and separating means receiving the emulsion from said electric field in said electric treater for separating the emulsion constituents.

16. In an electric dehydrator for emulsions adapted for use in conjunction with a pipe line formed of a plurality of sections, the combination of: an enclosing structure open at its ends to receive emulsion from one section of said pipe line and discharge treated emulsion into another section of said pipe line; a rod electrode in said enclosing structure and extending parallel to the direction of flow of said emulsion through said enclosing structure and being surrounded by the stream of emulsion moving through said enclosing structure; a supporting arm holding said rod electrode in position and extending transverse to the direction of flow of said emulsion through said enclosing structure; insulator means extending through said enclosing structure and providing an electric conductor electrically connected to said rod electrode for conducting a high potential current thereto; and potential-supply means connected to said enclosing structure and to said conductor for establishing an electric field in the space inside said enclosing structure and around said rod electrode to electrically treat the emulsion flowing through said space around said rod electrode.

17. In an electric treater for emulsions for use in conjunction with a section of pipe through which a stream of emulsion flows: walls forming a longitudinal passage communicating at one end with said section of pipe whereby said emulsion flows through said longitudinal passage in a stream which substantially fills said longitudinal passage; walls forming an insulator chamber to one side of said longitudinal passage communicating therewith but substantially removed from the main portion of said stream of emulsion; an electrode in said passage and in the path of travel of said stream of emulsion to be surrounded thereby; an insulator in said insulator chamber and supporting said electrode; and means for establishing an electric field in said passage adjacent said electrode.

18. A combination as defined in claim 17 in which said insulator terminates adjacent the inner end of said insulator chamber and thus terminates short of said main portion of said stream, and including an arm supported by said insulator and attached to said electrode and extending transversely into said stream of emulsion flowing through said longitudinal passage.

19. A combination as defined in claim 17 in which said insulator chamber extends upward from said longitudinal passage, and including low-back-pressure withdrawal means communicating with that end of said passage from which said stream of emulsion moves to permit gas to

be liberated from said emulsion and rise in said insulator chamber to surround said insulator.

20. In an electric treater for emulsions, the combination of: a container containing the emulsion to be treated; electrode means in said container for setting up an electric field therein; an insulator in one portion of said container and associated with said electrode means; orifice means around said insulator and discharging inside said container for flowing an envelope of liquid along the surface of said insulator in washing relationship therewith; and means for supplying to said annular means a liquid of higher dielectric strength than the emulsion whereby the surface of said insulator is washed with said liquid of higher dielectric strength to prevent accumulation thereon of the emulsion constituents.
21. In an electric treater for emulsions, the combination of: electrode means defining a treating space containing said emulsion; walls forming an insulator chamber communicating with said treating space but spaced therefrom; an insulator bushing extending through one of said walls and providing a conductor electrically connected to said electrode means; annular means in said insulator chamber around said insulating bushing and providing orifice means directing an envelope of liquid along said bushing in surrounding relationship therewith; and

means for supplying to said means a liquid of higher dielectric strength than said emulsion.

22. A method of protecting the exposed surface of an insulator extending into an electric treater, which method includes the steps of: introducing into said treater an emulsion of such character that it would tend to cause electric failure of said insulator if the emulsion constituents are brought into contact with said exposed surface; and washing said exposed surface of said insulator by flowing a thin moving envelope of dielectric liquid along said exposed surface to separate said exposed surface from any of said emulsion constituents in said electric treater.

23. A method of treating an emulsion flowing along a pipe line, which method includes the steps of: establishing a plurality of electric fields positioned at spaced sections along said pipe line, each of said fields being of sufficient intensity to coalesce the dispersed droplets of said emulsion into larger masses; moving the emulsion constituents successively through said fields without substantial separation of the treated constituents from each other during passage between said fields; and separating the emulsion constituents from each other after subjection to the last electric field.

WILLIAM WOELFLIN.
